UNITED STATES PATENT OFFICE.

SYLVANUS A. REED, OF NEW YORK, N. Y., ASSIGNOR TO THE REED PROPELLER CO. INC., OF NEW YORK, N. Y., A CORPORATION OF NEW YORK.

AERONAUTICAL PROPELLER.

Application filed May 12, 1924. Serial No. 712,646.

This invention relates generally to propellers for aeronautical use and it is particularly well adapted for use in conjunction with metal propellers.

5 In my U. S. Patent No. 1,463,556, dated July 31, 1923, and also in my pending application for patent, filed June 22, 1922, Serial No. 570,139, I disclose certain types of metal aeronautical propellers, and my present improvements are also applicable to said general types, but, of course, are not in any way limited thereto.

10 My present invention includes a simplification of structure whereby omitting the features needed for interchangeability with customary wooden propellers on the same steel hubs, a propeller may be obtained of greater efficiency and strength with less aggregate weight.

15 In some of my earlier forms of structure, the above mentioned adaptability for attachment to existing steel hubs employed a central expansion to permit making a large central hole to pass the end of the driving-shaft and smaller holes for the hub-bolts. In my present improvements, there is no central shaft-hole bored through the propeller, bolt-holes are reduced in number and long bolts are dispensed with. But more particularly I 20 gain in the total efficiency, because of a closer approximation which I am able to obtain to a true helix nearly up to the drive-shaft itself. I also gain the propulsive effect of the blades up to those points and in addition I 25 gain by the omission of a central boss, which is an obstruction to flight, is an additional weight and absorbs a certain amount of the driving power.

30 A true helical propeller passes through the driving axis in such a manner that the driving or thrust face is at a pitch-angle of 90°, and that type of section of a helical surface which constitutes an ideal propeller will be found to have around the longitudinal or diametrical axis of the propeller, a continuous twist, always in the same direction, right or left-handed, from one tip through the drive-shaft axis to the other tip. In my said patent and patent application, in order to accommodate the central shaft-hole and customary hub, I reversed this twist near the central region or hub and resumed the original twist beyond. In my present improvements I have a continuous twist in one direction from tip to tip of the blades.

35 It is obvious that to so form a propeller by twisting a single piece of elongated metal plate and to provide the same with the usual camber face forward and a flat face on the thrust side, the plate before twisting, as above described, will have the said chamber of one blade on one side of the original plate and the camber of the other blade on the reverse side of the plate. Then, after twisting to the appropriate pitch, always in one direction, both camber faces will be found on the same side, namely, the forward side of the twisted propeller.

40 In order to secure the propeller to the drive-shaft for safe transmission of torque and thrust several means are available with the peculiar construction and arrangement of this propeller, but I prefer, where possible, to omit the usual drive-shaft extension and to terminate the drive-shaft close to its forward bearing and secure thereto a metal body or shell, preferably of steel, with inclined side-slots, to receive and hold securely the propeller blades in position, said shell having a medial re-inforcing ring or strap, preferably of steel, passing through holes in the propeller and assisting in locking it securely in place.

45 With these and other objects in view, my inventions will be more fully described, illustrated in the drawings and then particularly pointed out in the claims.

50 In the said drawings:

Fig. 1, is a side elevation of the propeller and drive-shaft, with the attaching body or shell and its adjuncts in longitudinal section.

55 Fig. 2, is an underside view of the propeller and its shaft-attaching means, with the shaft omitted.

Fig. 3, is a side elevation of the structure, the view being at right-angles to that shown in Fig. 1.

60 Referring to the drawings, 1 is a portion of the outer end of the propeller drive-shaft, and 2 is a flange on the end thereof. The propeller is formed with blades 3 and 4, with a central connecting part 5, which contains or includes, indicated by the line 7—7, the axis of the propeller shaft, the arrow 6, showing the direction of rotation of the propeller. 65 The blades 3 and 4, have pitch-angles to the plane of rotation increasing in the well known way from tip toward the central part or hub, but instead of becoming merged into a massive boss near the central region, as in the case of 70

wooden propellers, or of being reversed in twist as in the case of certain forms of my metal propeller requiring a central shafthole, my improved propeller-blades continue to increase their pitch-angles so that at the point 7, at the axial line, they are at 90° , and it is noted that the direction of the twist around the longitudinal axis, indicated by the line 8-8 is in one direction from tip to tip, and that the leading-edge 9, of each blade crosses over the axial line to become the leading-edge 9, of the other, and as the trailing-edge 10, likewise crosses over to become the trailing-edge 10, of the other, the forward blade faces after twisting, as shown in view in Fig. 2, are both convex, and therefore before twisting they must have been on opposite sides of the original flat plate.

The attaching or hub body 12, which is preferably in the form of a hollow metal shell and cylindrical, though it may assume any form adapted for its purpose and which will serve to decrease air resistance, has a flange 13, at its inner end for engagement with the flange 2, on the end of the shaft and to which it is secured by short bolts 14. At diametrically opposite points, the walls of shell 12, are formed with inclined slots 15, closely fitting the central part 5, of the propeller which is inserted edgewise into the same from the lower open ends of the slots. The upper ends of the slots are closed and the length of the slots being the width of the central blade-connecting part 5, the inner edge of said part is drawn firmly against the shaft flange 2, by the bolts 14. These slots 15, extend longitudinally of the sleeve and in oblique direction and are made to accurately fit and accommodate the part 5, which passes transversely through the shell or hub 12.

A metal strap or ring 19, is passed around the exterior of the tubular hub 12, and through snugly fitting holes 16, formed in the central part 5, at opposite sides of said hub. The ends of the strap are drawn together and secured by bolting or welding, thus strengthening the shell 12, and at the same time, fixing the propeller against end play. The strap 19, may also be secured to the shell by screws 20, to anchor it securely in place. The propeller is thus held firmly against thrust and torque and relies for resistance to centrifugal force solely upon its own integrity without participation of the member or hub 12, which may therefore be made relatively light in weight.

The outer end of the shell is provided with a finishing cap 17, in the form of a hollow cone of thin material telescoped over the end, and secured thereto by screws, 18, and serving to diminish air resistance.

This novel form of propeller permits of the same being mounted edge-wise in respect to the drive-shaft, so that the axis of rotation is coincident with the transverse axis of the

propeller. This disposition of the propeller not only results in a lighter weight structure, but also simplifies the same, at the same time giving certain advantages in efficiency of operation.

My invention is not confined to the particular constructions of parts, as herewith disclosed, as various modifications may be made in several different parts, without, however, departing from the spirit of my invention.

The propeller is made preferably of a solid metal plate and of any well known suitable light-weight metal alloys, such as aluminum alloys, for example duralumin.

Having thus described my invention, what I claim and desire to secure by Letters Patent is:

1. An aeronautical propeller having a nonaxially perforated central part and oppositely extending blades connected therewith and crossing the driving-axis so that said axis is parallel with the wide dimension of said central part and said propeller twisted so that the trend of the twist is substantially continuous from end to end to equal resultant pitch-angles for each blade with the convex faces of both blades disposed on the same side of the propeller.

2. A single piece metal aeronautical propeller formed from an elongated relatively thin nonaxially perforated plate with blades convex on one side of one blade and convex on the other side of the other blade, and twisted in one direction from end to end to equal resultant pitch-angles for each blade.

3. A single piece metal aeronautical propeller formed from an elongated relatively thin nonaxially perforated plate with oppositely extending blades convex on one side of one blade and convex on the other side of the other blade, and twisted in one direction from tip to tip to equal resultant pitch-angles for each blade so that both convex faces are on the forward side of the propeller.

4. An aeronautical propeller having a helical twist about its longitudinal axis and formed from a blank having a central part with blade portions connected therewith and convex on one side of one blade portion and convex on the other side of the other blade portion, and the leading edge of one blade passing through the axis of rotation and becoming the leading edge of the other blade.

5. A propeller having a relatively flat central part to which the blades are connected, and a hub driving-member constructed and arranged so that said central part of the propeller passes transversely through it in locking engagement therewith to transmit torque and thrust, said flat central part lying substantially along the axis of rotation, and means for securing said central part against movement relatively to said driving-member.

6. A propeller having a comparatively thin central part to which the blades are con-

nected, a driving-member, said central part extending transversely through said driving member and extending substantially along the driving-axis thereof and in locking engagement therewith and means for securing the same in fixed relation.

7. A propeller having a comparatively thin central part to which the blades are connected, a driving-member, said central part extending transversely through said driving-member in the plane of the driving-axis thereof so that the transverse axis of said central part is coincident with said driving-axis, and means for securing said parts together.

8. A propeller having a central part to which the blades are connected, a hub comprising a body provided with a transverse passage extending along the axis of the hub for receiving said central part, said central part extending through said passage, and means for securing said parts together.

9. A propeller having a central part to which the blades are connected, a hub comprising a body having a flange at its inner end and provided with a transverse opening for receiving said central part, said central part extending through said opening and means for locking the parts together, a drive-shaft provided with a flange and means for attaching it to the flange of said hub body.

10. A propeller having a central part to which the blades are connected, a hub comprising a body having a transverse opening extending through it for receiving said central part, said central part extending through said opening, orifices in said central part upon each side of said body to the exterior thereof, and locking members passing through said orifices and secured to said hub body.

11. A propeller having a central part to which the blades are connected, a hub comprising a body having a transverse passage therethrough for receiving said central part, said central part passing through said passage in the body, said central part being formed with orifices lying to the exterior of said body, and a locking-member passing around said body and through the respective orifices and secured in such position.

12. A propeller having a central part to which the blades are connected, a hub comprising a tubular body, similarly disposed slots formed in the opposite walls of said body and open at one end thereof, but closed at the other, and said central part being inserted in said slots, and a closure for the open ends of said slots.

60 13. A propeller having a central part to

which the blades are connected, a hub comprising a tube flanged at its inner end and provided in its opposite walls with similarly arranged slots which open at said inner end of the tube, said central part being 65 mounted in said slots and fitting the same, perforations formed in said central part to the exterior of said tube, a strap passing around said tube and through said perforations in the central part and secured to said 70 tube.

14. A propeller having a central blade-connecting part with oppositely extending blades and twisted in one direction from end to end to equal resultant pitch-angles for 75 each blade so that the leading edge of one blade passes through the driving-axis and becomes the leading edge of the other blade, a hub comprising a body provided with a transverse passage for receiving said central 80 part, said central part being mounted through said passage and containing said driving-axis, and means for securing said parts together.

15. In an aeronautical propeller, a broad 85 and comparatively thin central nonaxially perforated mounting part having blades connected therewith and crossing the driving-axis so that the broad dimension is substantially parallel with said driving-axis, and 90 driving connections engaging the broad faces or sides of said central-part for driving the same.

16. In an aeronautical propeller, a non-95 axially perforated central mounting part formed broad and comparatively thin and having blades attached thereto and crossing the driving-axis so that the broad dimension is substantially parallel with said driving-axis, and driving connections for said part 100 comprising a member provided with a passage axially coincident with said driving-axis and having oppositely arranged openings through which said central-part extends with practically unobstructed spaces at the sides 105 of said central-part in the region of the driving-axis.

17. An aeronautical propeller having a central mounting part connecting the oppositely extending blades, the propeller being 110 of helical form about its longitudinal axis from tip to tip of the blades, and a tubular driving-member having the said central part secured diametrically across the tubular member so as to leave the opposite sides of 115 said central part unobstructed within the tubular member.

In testimony whereof, I have hereunto set my hand.

SYLVANUS A. REED.
